UNITED STATES PATENT OFFICE.

JAMES C. GOURLEY, OF HARTFORD, CONNECTICUT, ASSIGNOR TO THE SMYTH MANUFACTURING COMPANY, OF HARTFORD, CONNECTICUT, A CORPORATION OF CONNECTICUT.

MACHINE FOR SHAPING THE BACKS OF BOOKCASES.

Application filed May 13, 1924. Serial No. 712,969.

To all whom it may concern:

Be it known that I, JAMES C. GOURLEY, a citizen of the United States, residing at Hartford, in the county of Hartford and State of Connecticut, have invented a new and useful Improvement in Machines for Shaping the Backs of Bookcases, of which the following is a specification.

This invention relates to the type of machine designed for shaping the backs of bookcases or covers which is illustrated and described in United States Patent No. 1,230,292 granted on my application June 19, 1917. In the machine of that patent the cases, which comprise two more or less stiff sides flexibly joined to a back, are stacked in a magazine which is adjustable to accommodate various sizes and which one at a time are successively removed from the bottom of the magazine and by an adjustable feed carried along between adjustable guides over a former and between adjustable creasers of the size and style to impart the required shape to the back of the cases. The feed mechanism shown in the patent referred to comprises endless chains carrying feed blocks that are adapted to in succession engage the edges of the lowest case in the pile and push it from the magazine to the shaping mechanisms.

It is frequently desirable for purposes of adjustment or inspection or the removal of a particular case and for other reasons to clear the feeding and shaping mechanisms without stopping the machine, that is, to run out those cases which are in the process of being fed and acted upon without feeding other cases from the magazine. The object of the present invention is to provide such machines with simple, quickly operated means whereby the feeding of the cases from the stack in the magazine can be stopped without interrupting the actions of the other mechanisms.

This object is attained by arranging means in connection with the support that extends longitudinally of the machine beneath the magazine and over which the cases are carried by the feed blocks on the chains to the creasers and former, whereby the pile of cases in the magazine can be instantly lifted so as to raise the lowest case in the magazine above the plane of movement of the feed blocks and thus interrupt the removal of

the cases from the magazine without interfering with the running of the mechanisms. 55

In the accompanying drawings Fig. 1 shows a plan of the portion of the machine to which the improvement is applied. Fig. 2 shows a side elevation of the same. Fig. 3 shows, on larger scale, an end elevation of the machine. Fig. 4 shows a side view of the supporting bar and case lifting plates. Fig. 5 is a plan of the bar and lifting plates.

The magazine for receiving the stacks of cases consists of two upright plates 1 that have their lower edges attached to the supporting bars 2 which are movably mounted on the frame bed 3 in such manner that by moving the bars in and out the plates of the magazine may be adjusted toward or from each other for accommodating cases of different shape and sizes. These bars extend parallel the length of the bed and are utilized to support the edges of the cases as they are fed through the machine. The bars also carry the wings 4 which guide the cases as they are fed along from the magazine. The supporting bars carrying the magazine and the guiding means are adjustable toward and from each other by means of screw shaft 5, as more particularly pointed out in the patent referred to. 75

The feed chains 6 pass around sprocket wheels 7 on a shaft 8 and travel in channels 85 in the top of the bed beneath the lower open end of the magazine. Removably fastened to the chain links at suitable intervals are blocks 9 and attached to each block is a pusher plate 10 the front end 90 of which is adapted to extend above the block sufficiently to engage the edges of the lowest case of the pile in the magazine. On the top of the bed between the channels which form the guides for the chain and feed blocks is a fixed bar 11 to the upper face of which is fastened the shaping former 12. As the cases are fed along by the blocks on the feed chains with their sides resting on the supporting bars and between the guide wings the backs travel above the former. The feeding mechanism carries the cases so that the edges of the backs pass between two creaser bars 13, as described more in detail in the former patent. 100

In carrying out this invention, to each

2
side of the central bar 11 which extends longitudinally of the machine beneath the magazine is applied a plate 14 which is fastened so that it may be reciprocated longitudinally and be given a vertical movement. These plates near each end are desirably provided with slots 15 which have a portion inclined and a portion horizontal, Fig. 4. Projecting from the central bar 10 into these slots are pins 16. The ends of the plates are connected by a cross head 17 through an opening in which extends a hand lever 18 the lower end of which is by a pintle 19 pivoted between ears 20 of a bracket that is fastened to the frame of the machine. When the handle is pulled outward the co-operation of the slots in the plates and the pins projecting from the central bar is such that the plates are drawn down to positions in which their upper edges are substantially flush with the top of the bar. When the handle is pushed inward the inclined sections of the slots acting on the pins tends to lift the plates and carry their edges above the level of the bar. With the handle pushed way in so that the pins extend through the horizontal sections of the slots the plates are held in their lifted positions. During the ordinary 20 operation of the machine the plates are held down in their lowest positions. When in these positions the pusher plates on the blocks attached to the feed chains can engage and push the lowest case from the stack in the magazine and deliver it unto the former between the creasers. If it is desired for any reason to interrupt the removal of any of the cases from the magazine the handle is pushed in and the plates 30 lifted so as to raise the lowest case above the plane of movement of the pushing plates on the blocks carried by the feed chains. With the plates in their raised positions no case will be fed from the magazine but the action of the other mechanisms of the machine will not be interrupted.

The invention claimed is:

1. In a machine for shaping the backs of book cases the combination with the magazine for retaining the cases, creasers and former for shaping the backs of the cases and means for feeding the cases from the under side of the magazine to between the creasers and over the former, of means for raising the lowest case in the magazine above the plane of movement of the feeding means.

2. In a machine for shaping the backs of book cases the combination with the magazine for containing the cases, creasers and former for shaping the backs of the cases and feeding blocks for engaging the lowest case in the magazine and feeding it be-

tween the creasers and over the former, of means for raising the lowest case in the 65 magazine above the plane of movement of the feeding blocks.

3. In a machine for shaping the backs of book cases the combination with the magazine for retaining the cases, creasers and former for shaping the backs of the cases and means for feeding the cases from the under side of the magazine to between the creasers and over the former, of means for lifting the cases in the magazine and holding 70 the lowest case above the plane of movement of the feeding means.

4. In a machine for shaping the backs of book cases the combination with the magazine for retaining the cases, creasers and former for shaping the backs of the cases and means for feeding the cases from the under side of the magazine to between the creasers and over the former, of vertically 80 movable plates for raising the lowest case 85 in the magazine above the plane of movement of the feeding means, and means for raising and lowering said plates.

5. In a machine for shaping the backs of book cases the combination with the magazine for retaining the cases, creasers and former for shaping the backs of the cases and feeding means for feeding the cases from the under side of the magazine to between the creasers and over the former, 90 of longitudinally and vertically movable plates for raising the lowest case in the magazine above the plane of movement 95 of the feeding means, and means for moving said plates longitudinally and vertically.

6. In a machine for shaping the backs of book cases the combination with the magazine for retaining the cases, creasers and former for shaping the backs of the cases 105 and feeding means for feeding the cases from the under side of the magazine to between the creasers and over the former, of a supporting bar, plates movably applied to said bar, below the magazine and pins 110 and inclined slots connecting said plates to said bar, whereby the longitudinal movement of the plates with relation to the bar imparts a vertical movement to said plates.

7. In a machine for shaping the backs of book cases the combination with the magazine for retaining the cases, and means for normally feeding the cases from the under side of the magazine, of means below said cases for raising the lowest case in the 120 magazine above the plane of movement of the feeding means, whereby the feeding of the cases from the magazine may be interrupted.

JAMES C. GOURLEY.
